(57) **CLAIM**

The ornamental design for an autonomous coverage vacuum cleaner, as shown and described.

DESCRIPTION

FIG. 1 is a perspective view of an autonomous coverage vacuum cleaner showing my new design,
 FIG. 2 is a front elevational view thereof,
 FIG. 3 is a rear elevational view thereof,
 FIG. 4 is a left side elevational view thereof,
 FIG. 5 is a right side elevational view thereof; and,
 FIG. 6 is a top plan view thereof.
